FABRICATED WOOD FLOOR

Frank W. Cherry, Kenilworth, Ill., assignor to
 Lug-Lox Flooring Company, a corporation of
 Illinois

Application September 22, 1932, Serial No. 634,380

5 Claims. (Cl. 20—8)

The present day method of laying wooden floors, one board at a time, scraping or sanding them, and then giving them the desired surface coatings is very costly, because all of the operations are performed by hand under conditions not best adapted to keep the cost down.

The object of the present invention is to make it possible to produce a completely finished wooden floor, ready for use, without requiring any appreciable amount of labor in the process of laying the floor, and without requiring any labor to give to the floor the desired surface finish after it has been laid.

In carrying out my invention, I assemble at a mill, factory or central plant wood floors in finished units or sections; each unit or sections consisting of ordinary tongue and groove, or other, floor boards held firmly together by metal fastenings. These units or sections can be easily handled and quickly installed upon any suitably prepared subfloor; thereby producing a complete, uniform floor by the mere simple act of assembling the several units or sections which constitute it. Consequently there is a great saving of time in the laying of the wooden floors in a building because the steps of nailing down the floors, one board at a time, of scraping and sanding, and of adding surface coatings are eliminated. This saving in time in completing a building, or in laying a floor anywhere, is an advantage in addition to that resulting in the savings effected in the cost of manufacturing the floor in the mill, factory or central plant over the old methods.

The floor boards of each unit or section must, of course, be held together so that the upper faces thereof will initially be flush with each other and will remain so. This I accomplish by securing the floor boards to underlying metal strips, bars or rails. I prefer to employ bars or rails which, although shallow, will be sufficiently sturdy to hold the sections flat. If the boards were secured to wooden beams, warping of the wood would make it impossible to produce a floor which would remain flat even if it were flat initially. The boards are preferably fastened to the metal rails or the like by means of clips interlocked at their lower ends with the latter and extending up into the joints between, and interlocked at their upper ends with, the boards. With this arrangement, the boards may be of the ordinary tongue and groove type, or of any other type without exposing any of the fastenings at the upper side or face of the floor.

In carrying out my invention I have produced a novel construction and arrangement which will

permit the tongues of ordinary tongue and groove floor boards to seat themselves in the grooves of adjacent boards in precisely the same way as in a nailed floor, while providing room for the holding elements of clips that draw the boards down against the rails. Therefore, viewed in one of its aspects, the present invention may be said to have for its object to modify floor boards of the tongue and groove type so that, while the tongues and grooves function precisely as heretofore, pockets or recesses are afforded to receive and seat elements on holding clips each extending upwardly into the joint between two boards and interlocked with both.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figures 1, 2 and 3 are horizontal sections through a room, showing the progress of laying therein a floor composed of three units or sections, Fig. 1 showing the first section in position, Fig. 2, the first two sections, and Fig. 3, all three sections; Fig. 4 is a section, on an enlarged scale on line 4—4 of Fig. 3, showing the third and last section being brought into position beside the second section; Fig. 5 is a view similar to Fig. 4, showing the third section in its final position of adjustment; Fig. 6 is a section, on a larger scale than Figs. 4 and 5, on a plane extending transversely of the boards and longitudinally through one of the rails, only fragments of two of the boards being shown; Fig. 7 is a section through one of the floor units or sections taken on line 7—7 of Fig. 6, that board which is at the left in Fig. 6 being shown in elevation, as is the clip and that board which is at the right in Fig. 6 being entirely omitted; Fig. 8 is a perspective view of a fragment of one of the boards showing one of the seats or pockets to receive the flanges on one of the holding clips; and Fig. 9 is a perspective view of one of the holding clips.

Referring to Figs. 1 to 5 of the drawings, A represents a room having a rough or other subfloor B on which a finished wooden floor is to be laid. In accordance with my invention, the wooden floor is preformed or fabricated into a number of units or sections which, when laid on the floor of the room, edge to edge, will cover the latter. The room has been shown as being just wide enough to accommodate three sec-

tions which I have indicated at C, D, and E; these sections being of various sizes and shapes due to the shape of the room. The several units or sections may be laid directly on the subfloor 5 B or on a cushioning pad F overlying the subfloor B.

Each floor section is made up of the necessary number of floor boards 1 of the tongue and groove or any other type. In the arrangement shown, 10 the boards are of the tongue and groove type and the invention will be described and explained in connection with this particular embodiment, although not limited thereto. The floor boards are laid crosswise of and rest upon 15 suitable shallow metal strips, bars or rails 2, preferably parallel with each other and spaced apart a short distance from each other. In the arrangement shown, each of the rails is in the form of a stiff trough or channel, the upper marginal portions of whose side walls are turned or bent inwardly at right angles thereto to form flanges 3, 3. Excisions, which may be saw cuts, are made in the edge of each board, these excisions extending inwardly through the under 20 side of the tongue and a short distance into the body of the board. The excisions are so distributed that there will be one above each rail. Therefore, as best shown in Fig. 8, each board has above each of the rails a flat recess 4 cut 25 into the under face of its tongue 5 and merging at its inner end into a shallow pocket 6 extending into the body of the board.

The boards are shown as being fastened to the rails by means of clips G each composed of a 30 stem or shank portion 7 of about the same width as the internal width of one of the troughs or channels in the rails, and provided with notches 8, 8 in its side or end edges to receive the flanges 3, 3 of one of the rails; together with laterally-projecting flanges 9 and 10 at the top. The metal of the flanges 9 and 10 has a thickness about equal to the vertical height or depth of the recesses 4 and the pockets 6. The over-all width of each clip at the top of the clip, measured at right angles to the plane of the shank or stem, is somewhat less than the distance between the inner end of one of the pockets 6 and the inner end or bottom of the groove 11 in the adjacent board, when the tongue in one board is 40 fully entered into the groove of the adjacent board. Furthermore, the distance between the notches 8 and the flanges in each clip is such that, when a clip is interlocked with a rail and is then slid along the rail until its flange 9 enters the pocket 6 in a board resting on the rail, that board will be held tightly against the top of the rail. A portion of the flange 9 and the flange 10 will be seated in the recess 4 in the under side of the tongue, and thus there will be 45 no interference with the entry of the tongue and the flange 10 into the groove in the next board when the latter is set on the rails and moved along the same until it engages with the first board.

It is therefore evident that a floor unit or section may be quickly assembled and then be finished in any desired manner in the factory, mill or central plant, and then need only be laid down beside other units or sections on a prepared subfloor to produce a floor finished and ready for use.

I prefer that the rails project beyond at least one edge of each floor unit or section so as to underlie the adjacent marginal portion of the

next section. I therefore prefer so to position the rails on two adjacent or consecutive floor sections in such a manner that they will not align with each other; thus permitting the projecting ends of the rails on one section to pass underneath and adjacent section without being interfered with by the rails forming part of the latter section.

After one of the floor units or sections has been laid down, it will be seen that there is a row 10 of clips G, along the exposed edge in position to enter into the groove in the edge of the next unit or section. This is best shown in Fig. 4 where the section D has been placed in its final position while the section E has been laid down 15 but is still spaced apart a short distance from section D. When section E is moved toward the left in Fig. 4, the projecting tongue of section D will enter the groove 11 in the advance edge of 20 section E; so that the clips associated with this tongue will be interlocked with section E just as though the last board in section D and the first board in section E were adjacent boards in the same floor section. In the same way the flanges 9 on the advance edge of section E will enter 25 properly placed recesses and pockets in the edge of section D.

It will thus be seen that a completely finished floor may be laid in a very short time, and be 30 immediately ready for use. Therefore, the cost of the work that has to be done on the job is so small as to be of little consequence; the actual work of assembly of the individual boards and of smoothing and surface-finishing the floor being all done in the mill at a much lower cost 35 and more effectively than could be done by hand on the job. As a result, fine floors, finely finished, may be had at a cost much lower than heretofore and even much lower than that of floors of greatly inferior workmanship and finished in the old manner.

It may be desirable to provide means to insure 40 that one floor section will not pull away from another. This can conveniently be accomplished by laying on the subfloor some strips, bars or 45 rails H, similar to the member 2, long enough to extend across the width of the room and fastening the floor units or sections to these additional elements. In this way the floor is tied together across its entire width and no separation of one unit or section from another can 50 take place after the floor has been laid.

I claim:

1. A floor board of the tongue and groove type having short sections removed at intervals 55 from the under side of the tongue while the overlying parts of the tongue remain intact.

2. A floor board of the tongue and groove type having at intervals along the under side of the tongue shallow recesses extending transversely 60 across the tongue, and there being shallow pockets in the edge of the body of the board in registration with said recesses.

3. A floor board of the tongue and groove type having short sections removed at intervals from the under side of the tongue to provide between the tongue and the underlying lip of a cooperating board pockets or channels whose vertical depth is the same as the thickness of a metal 65 in a sheet metal clip adapted to enter the grooves to hold the boards down.

4. A floor board of the tongue and groove type having sections removed at intervals from the under side of the tongue, said sections being 70

much longer, measured lengthwise of the board, than either the width or thickness of the tongue.

5. A floor board of the tongue and groove type having sections removed at intervals from the under side of the tongue and providing pockets, the vertical depth or height of each pocket being

only a small fraction of the vertical width or thickness of the tongue and the length of each pocket, measured lengthwise of the board, being much greater than the width or thickness of the tongue.

5

FRANK W. CHERRY.
